UNITED STATES PATENT OFFICE.

WILLIAM H. WIGGIN AND FRANK L. WIGGIN, OF LOWELL, MASSACHUSETTS.

TURN-OUT FOR STORE-SERVICE TRACKS.

SPECIFICATION forming part of Letters Patent No. 310,765, dated January 13, 1885.

Application filed December 6, 1884. (No model.)

To all whom it may concern:

Be it known that we, WILLIAM H. WIGGIN and FRANK L. WIGGIN, citizens of the United States, residing at Lowell, in the county 5 of Middlesex and State of Massachusetts, have invented certain new and useful Improvements in Turn-Outs for Store-Service Tracks, of which the following is a specification.

Our invention relates to that class of store-10 service apparatus in which the carriers travel upon tracks composed of parallel rails; and our invention consists in means, fully de-15 scribed hereinafter, whereby to secure a practically continuous track whether the carriers travel upon the main rail or from the latter to the branch, one of the tracks being at all times unbroken.

In the drawings, Figure 1 is a longitudinal 20 section of the turn-out of a store-service rail-25 way, illustrating our invention. Fig. 2 is the same, showing the parts in a different position. Fig. 3 is a plan view. Fig. 4 is a section on the line 1 2, Fig. 3, looking in the direction of the arrow.

25 A A' A² are the rails of the main track of a store-service apparatus, and B B' are the rails of the turn-out or branch track, the rail B constituting a continuation of the rail A, as usual, and the rails A² B' meeting to form 30 the ordinary point, x.

The branch track, instead of being open at the point where it merges with the main track, is barred by the supplemental rail A³, which constitutes in fact a part of the main track, 35 which is therefore continuous or unbroken, so that balls or other carriers will not, under ordinary circumstances, be deflected from the said main track, and the branch track will be closed. A second supplemental rail, B², ar-40

ranged to form a continuation of the turn-out track between the point x and the rail A' of the main track, is pivoted by a pin, a, to the inside of the rail A', and is counterweighted, (or acted upon by a spring, y, Fig. 1,) so that 45 it will tend to rise at the end nearest the point x, with its edge z slightly above that of the rail A³, the said rail, B², having a notch, i, beneath the rail A³, as shown. By this arrangement of rails the adjustment of the rail 50 B² may be the means of causing the carriers to travel upon either the main track or to pass therefrom to the branch. Thus, when the rail

B² is lowered, as shown in Fig. 1, the carriers will find their bearing upon the rail A³, and will continue upon the main track; but when the rail B² is raised to the position shown in Fig. 2, its edge z will be above that of the rail A³, and will present a bearing for the carriers upon which they will move above the rail A³, and which will conduct them to the side track. 60 In either case, according to the adjustment of the rail B², there will be a practically unbroken track, and the carriers will travel smoothly and without jar or interruption either upon the main line or to the turn-out 65 or branch. Where the carriers are graduated by their weight, the adjustment or proportion of the weight W upon the rail B², or the tension of the spring y, may be made the means of automatically directing the carriers. Thus, 70 where the carriers are sufficiently heavy they will bear upon and depress the rail B², and will thus be brought in contact with the rail A³, which will cause them to be brought upon the main track; but when the carriers are 75 light the rail B² will maintain its elevated position, and the carriers will be deflected thereby to the siding or branch. When the carriers are graduated according to their size, suitable appliances should be employed 80 whereby the rail B² is automatically adjusted. Thus two jointed arms, b c, may be interposed between the rail B² and a bracket or bearing, D, the arm b being jointed to the rail B², and the arm c being jointed to the bracket, as 85 shown.

To the middle joint, p, is connected a rod, d, which is attached at its opposite end to an arm, e, projecting from a shaft, f, supported in bearings at the side of one of the rails, and 90 a shaft, g, extends from this shaft across the main line in such position that it will be struck by the larger balls passing upon said line. As the arm g is carried in the direction of the arrow, Fig. 3, the rod d will be drawn back in 95 the direction of its arrow, Fig. 1, and the rods b c are brought to an angle to each other, as shown in Fig. 1, so that the rail B² will sink under the weight of the ball, which will then pass along the main track. After the ball has 100 passed from contact with the rail B² the latter will rise to the position shown in Fig. 2, and the arms b c will be brought into line and support the rail B² in its elevated position, so that

the smaller balls will pass to the branch. By this means the graduated balls are made the means of automatically presenting continuous tracks, both for the main line and the branch line, thereby avoiding the objections incident to the use of switch-points, which, when improperly adjusted, interfere with the movements of the balls and result in their derailment, and which at times leave both tracks open.

It will be evident that the rail B² may be fixed and the rail A³ movable, and that any suitable locking means may be used for securing the movable rail, and that the latter, instead of swinging on a pivot, may rise and fall vertically.

Without limiting ourselves to the precise construction and arrangement of parts shown, we claim—

20 1. The combination, with the continuous track of a railway, of a vertically-adjustable rail constituting a continuation of the branch track, and extending between the point and the rail of the main track, substantially as set forth.

25 2. The combination, in a railway, of a main track, a branch track, a fixed rail constituting a part of one of the tracks to make the latter an unbroken track, and a movable rail constituting part of the other track, crossing the fixed rail, and capable of adjustment to bring its upper edge above that of the fixed rail, substantially as set forth.

30 3. The combination, in a railway turn-out, of a continuous track and a branch track provided with a movable rail crossing the inner rail of the continuous track, and capable of vertical adjustment to bring its edge above or below that of the said inner rail, substantially as set forth.

35 4. The combination of the continuous track, branch track, and movable rail constituting a part of the branch track, counterbalanced substantially as and for the purpose specified.

40 5. The combination of the continuous track,

branch track, and movable rail constituting part of the branch track, notched for the passage of the inner rail of the continuous track and vertically-adjustable, substantially as specified.

50 6. The combination of the continuous track, branch track, and pivoted, notched, and counterbalanced rail constituting part of the branch track, substantially as specified.

55 7. The combination, with the continuous track, branch track, and vertically movable rail of one of the tracks, of a movable arm extending over the main track, and connections between the arm and the movable rail, substantially as and for the purpose set forth.

60 8. The combination, in a store-service railway, of a continuous track, a branch track, a movable rail constituting a part of one of the tracks, and connections between the rail and an arm arranged adjacent to the main track, to be struck by graduated carriers thereon, substantially as specified.

65 9. The combination, in a railway turn-out, of a vertically-movable rail crossing the inner fixed rail of one of the tracks, an arm arranged adjacent to the track, to be struck by graduated carriers thereon, and connections, substantially as described, whereby the movement of the said arm alters the vertical position of the movable rail, substantially as specified.

70 10. The combination, with the main track and branch track, of a fixed rail, A³, constituting a continuation of one of the tracks, and a movable rail, B², constituting a continuation of the other track, and vertically adjustable to bring its edge above or below that of the rail A³, substantially as set forth.

75 In testimony whereof we have signed our names to this specification in the presence of two subscribing witnesses:
